(57) **CLAIM**

The ornamental design for an imaging device, as shown and
described.

DESCRIPTION

FIG. 1 is a perspective view of an imaging device showing our
new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of the imaging device in FIG. 1
shown in an operational configuration; and,

FIG. 9 is a right side elevational view of the imaging device
shown in FIG. 8.

Broken lines and entirely unshaded portions contained within
broken lines are not claimed.
